(57) **CLAIM**

The ornamental design for portion of a front of a scanner, as shown

DESCRIPTION

FIG. 1 is a perspective view of a portion of a front of a scanner showing our new design;

FIG. 2 is a front view thereof;

FIG. 3 is a left side view thereof;

FIG. 4 is a right side thereof;

FIG. 5 is a plan view thereof;

FIG. 6 is a bottom view thereof;

FIG. 7 is a rear view thereof;

FIG. 8 is a perspective view of an alternative embodiment of a portion of a front of a scanner showing our new design;

FIG. 9 is a front view of the portion of a front of a scanner of FIG. 8;

FIG. 10 is a left side view of the portion of a front of a scanner of FIG. 8;

FIG. 11 is a right side view of the portion of a front of a scanner of FIG. 8;

FIG. 12 is a plan view of the portion of a front of a scanner of FIG. 8;

FIG. 13 is a bottom view of the portion of a front of a scanner of FIG. 8;

FIG. 14 is a rear view of the portion of a front of a scanner of FIG. 8;

FIG. 15 is a perspective view of another embodiment of a portion of a front of a scanner showing our new design;

FIG. 16 is a front view of the portion of a front of a scanner of FIG. 15;

FIG. 17 is a left side view of the portion of a front of a scanner of FIG. 15;

FIG. 18 is a right side of the portion of a front of a scanner of FIG. 15;

FIG. 19 is a plan view of the portion of a front of a scanner of FIG. 15;

FIG. 20 is a bottom view of the portion of a front of a scanner of FIG. 15; and,

FIG. 21 is a rear view of the portion of a front of a scanner of FIG. 15.

The broken lines shown form no part of the claimed design.
